(57) **CLAIM**

I claim the ornamental design for a modular razor cartridge clasp, as shown and described.

DESCRIPTION

FIG. 1 is a right side perspective view of the modular razor cartridge clasp, the left side perspective view being a mirror image thereof;

FIG. 2 is a bottom perspective view thereof;

FIG. 3 is a top perspective view thereof;

FIG. 4 is a left side elevational view thereof;

FIG. 5 is a rear elevational view thereof; and,

FIG. 6 is a top plan view thereof.
